CLAIM

The ornamental design for a nasal interface, as shown and described.

DESCRIPTION

FIG. 1 is a top and right front perspective view of a first embodiment of a nasal interface showing my design;

FIG. 2 is a right side view thereof;

FIG. 3 is a left side view thereof;

FIG. 4 is a top plan view thereof;

FIG. 5 is a bottom view thereof;

FIG. 6 is a plan view looking down the bore of the nasal interface;

FIG. 7 is a plan view looking down the bore of the nasal interface with the top side showing;

FIG. 8 is a top and right front perspective view of a second embodiment of the nasal interface;

FIG. 9 is a right side view thereof;

FIG. 10 is a left side view thereof;

FIG. 11 is a top plan view thereof;

FIG. 12 is a bottom plan view thereof;

FIG. 13 is a plan view looking down the bore of the nasal interface;

FIG. 14 is a plan view looking down the bore of the nasal interface with the top side showing; and,

FIG. 15 is right front elevational view showing the first and second embodiments of the nasal interface connected to a nasal interface system shown in dotted lines.

The broken lines showing the exhaust ports in the drawings are for illustrative purposes and forms no part of the claimed design.
